(57) **CLAIM**

The ornamental design for a viewing device, as shown and described.

DESCRIPTION

FIG. 1 is a front perspective view of the viewing device in the present invention with a viewing arm having an electronic display being attached to one side of the viewing device.

FIG. 2 is a front view thereof.

FIG. 3 is a rear view thereof.

FIG. 4 is a top view thereof.

FIG. 5 is a bottom view thereof.

FIG. 6 is a left side view thereof.

FIG. 7 is a right side view thereof.

FIG. 8 is a side perspective view thereof.

FIG. 9 is a front perspective view with the viewing arm folded up.

FIG. 10 is a side perspective view thereof with the viewing arm detached.

FIG. 11 is a front perspective view thereof with the viewing arm attached on an opposite side of the viewing device; and, FIG. 12 is a front perspective view thereof with the head band adjusted in an extended position.

The viewing device in the present invention is an electronic viewing device having a head band, that can be worn on the head of a user as an audio visual headset, and images and sound generated by the viewing device can be viewed and heard.
